(57) **CLAIM**

The ornamental design for a wedging cutting assembly, as shown and described.

DESCRIPTION

FIG. 1 is a pictorial view of a wedging cutting assembly according to the invention.

FIG. 2 is an exploded pictorial view of the components of the wedging cutting assembly shown in FIG. 1.

FIG. 3 is a front exploded view of the components of the wedging cutting assembly shown in FIG. 2, the rear view being identical.

FIG. 4 is a right side exploded view of the components of the wedging cutting assembly shown in FIGS. 2 and 3, the left side view being identical.

FIG. 5 is a top view of the wedging cutting assembly components shown in FIGS. 1–4.

FIG. 6 is a bottom view of the wedging cutting assembly components shown in FIGS. 1–5; and,

FIG. 7 is an enlarged pictorial view from above the cradle component of the wedging cutting assembly shown in FIGS. 2–4.
